UNITED STATES PATENT OFFICE.

ALBERT L. SWIFT, OF CHICAGO, ILLINOIS.

DESIGN FOR A LAMP-PEDESTAL.

No. 39,676.

Specification for Design.

Patented Dec. 1, 1908.

Application filed January 9, 1908. Serial No. 410,065. Term of patent 7 years.

To all whom it may concern:

Be it known that I, ALBERT L. SWIFT, a citizen of the United States, residing at Chicago, in the county of Cook and State of Illinois, have invented a certain new, original, and ornamental Design for Lamp-Pedestals, of which the following is a specification, reference being had to the accompanying drawing, forming a part thereof.

The design consists of a base presenting the appearance of two square blocks of unequal dimensions superposed, the smaller centrally upon the larger, a pedestal mounted centrally upon said base, said pedestal being of rectangular cross sectional form and of equal and uniform cross sectional dimen-

sions throughout its entire height with a central longitudinal groove of considerable depth in and extending the full length of each side or face, and a square cap surmounting the pedestal.

The figure on the drawing is a perspective view of a lamp pedestal showing my new design.

I claim:

The ornamental design for a lamp pedestal, as shown and described.

ALBERT L. SWIFT.
